UNITED STATES PATENT OFFICE.

CHARLES E. DRAKE, OF NEW YORK, N. Y.

SHIP-SALVAGING APPARATUS.

1,378,843.

Specification of Letters Patent.

Patented May 24, 1921.

Application filed September 14, 1920. Serial No. 410,197.

To all whom it may concern:

Be it known that I, CHARLES E. DRAKE, a citizen of the United States, residing in New York, in the county of Bronx and State of New York, have invented certain new and useful Improvements in Ship-Salvaging Apparatus, of which the following is a specification.

The main object of this invention is to provide a practical apparatus and means combined therewith for making adequate connections with the hull of a submerged ship whereby the same may be safely raised at a comparatively low cost.

15 A further object is to provide brace frame elements, contactable with the hull, adapted to guide the combined drill and raising bars, and which afford a secure mechanical purchase for the bars when in the act of 20 raising the ship.

These and other like objects, which will become apparent as the description progresses, are attained by the novel construction, combination and arrangement of parts 25 hereinafter described and shown in the accompanying drawings, forming a material part of this disclosure, and in which:—

Figure 1 is a perspective view, partially in section, and largely diagrammatic, illustrating in general the application of the invention.

Fig. 2 is a perspective view showing the combined drill, lifting bar and its brace bracket.

35 Fig. 3 is an enlarged fragmentary sectional view of a fragment of a ship's hull and drill bar.

Fig. 4 is a transverse sectional view of a preferred form of diving bell and its principal appurtenances.

When ships are sunk at a depth no greater than at which divers can work, cables can be secured in the port holes, passed beneath the hull or otherwise as may be deemed 45 expedient.

If the ship is at a greater depth such ordinary means are not available and other means for attaching lifting cables must be used in salvaging the ship.

50 This invention comprises means for attaching such cables to ships at any depth from the surface, in a relatively easy, convenient and certain manner.

Referring now to the drawings in detail, 55 particularly Fig. 1, the numeral 10 designates a sunken ship resting on the bottom of

a body of water, 11 the tender or ship for the divers and other operators, containing a power plant for providing electricity, compressed air, cable haulage means, and like 60 necessary appurtenances relating to the purpose, one or more of the tenders being employed as may be necessary.

A diving bell of peculiar construction as characteristic of certain phases of the invention is indicated generally by the numeral 12, the same being an oblong rectangle enabling several operations to be conducted simultaneously.

The diving bell 12 is attached by cables 70 14 to the tender 11, rings 15 being fixed to the top of the bell at each end, the bell being further supported by rods 16 attached to its bottom, the rods being telescopic or rigid as preferred; other rods 17 arranged 75 diagonally, in order to take the thrust of the drills, passing through stuffing boxes 18 at the outer lower corners of the bell.

The rods 17 extend up through the floor 20 of the bell and transverse partition 21 80 above which the operators work, the ends of the rods being provided with teeth in the manner of racks 22 engaged by gears 23 fixed on spindles 24 along side ratchets 25 held in adjustment by spring pressed 85 pawls 26.

The gears are rotated by pinions 27 turned manually by cranks 28 thus raising or lowering the rods from the interior of the bell as may be desired and it is evident similar 90 adjusting means may be applied to the rods 16.

Access to the bell may be had, through the door 30 at one end to the upper compartment 31 and from it to the lower compartment 33 by the trap door 32, it being understood that the door, when closed is substantially air and water tight.

A stout flexible tube 35 conveys air from the tender to the compartment 31, and a 100 cable 36 similarly connected, acts as a conveyer for electric conductors 37, 38 and 39 leading respectively to the switch 40, telephone 41 and electric lights 42, provided with reflectors 43 arranged adjacent to port 105 holes 44 covered by lenses 45.

The drilling mechanism is in the lower compartment 33 and consists of one or more electric motors 48 fastened to the floor 20 and energized by current delivered through 110 the wires 49 from the switch 40.

Standards 50, also secured to the floor 20,

are formed with bearings 51 in which are mounted the hubs of gears 52 driven by the motors.

Passing through the gear hubs are shafts 55 having keys 56 by which they are driven and are free to move lengthwise.

The outer ends of these shafts are guided and supported in stuffing boxes 57 set in the wall of the bell and through which they extend, terminating in forks 58 exterior of the bell.

Held between collars 59, pinned to the shafts, are sleeves 60 having racks 61 on their upper surfaces engaged by pinions 62 mounted on spindles 63 adjacent to bevel gears 64 meshing with mating gears 65 on the ends of shafts 66.

The spindles 63 rotate in bearings 67 and the shafts 66 are guided by bearings on the partition 21 and at their upper ends by brackets 68, above which they are provided with operating hand wheels 70 that upon being turned, obviously advance or retract the shafts 56.

Engageable with the protruding ends of the shafts are sockets 72 carrying transverse pins 73 enterable between the forks 58 and fixed to the opposite ends of the sockets are round bars 74 terminating in drill points 75.

The driving connection between the drill bar 74, and shaft 56 is only suggestive, as obviously any slip or screw joint connections may be used.

Adjacent the drill ends of the bars 74 are slots 77 loosely containing stop or latch plates 78 pivoted on pins 79, the function of these latch plates being to drop by gravity after the drill has pierced the hull 10 and armor plate 10' if such exist, preventing retraction of the drill bars 74.

These bars preferably have annular grooves 80 at suitable distances from the drill ends around which are secured the ends of haulage cables 82 extending up through the water to winches or like hoisting devices on the tender 11.

An important part of the invention is the combined guide and brace frames for the drill bars, the same consisting of triangular frames, their bases 85 being adapted to make intimate contact with the hull of the ship to be raised, the bars being joined to relatively narrow parallel elements 86 by diagonally disposed integral elements 87 and 88, respectively upper and lower, the cables 82 passing through openings in the upper elements 87 while the drill bars 74, are guided horizontally in openings formed centrally in the elements 86 and 85.

In operation, the position of the sunken ship having been ascertained by divers or otherwise, the tender ships are anchored adjacent and one or more of the diving bells lowered in close proximity to the sunken

These bells are then adjusted to stand level at a suitable height to bring the drills, which are preferably staggered in different planes, into proper position, the guide frames placed against the hull and connection between the drill bars and shafts established.

Upon starting the motors the drills are caused to revolve and may be advanced against the hull by the wheels 70.

When the latches 78 have passed through the hull they will drop by gravity and the shafts retracted.

The work can be watched as it proceeds through the lenses 45 which also dispense light where it is required.

Due to the fact that several drills are used simultaneously the work is quickly performed and it is relatively easy to move the diving bells to a new position.

When a sufficient number of holes have been drilled in the hull of the sunken ship, the cables 82 are hauled up, and, as they are attached to the bars closely to the hull, exert an effective pull.

Due to the peculiar construction of the drill guide frames, which with the drills are left with the hull, the drill bars are provided with an effective leverage, preventing them from bending up and because of the latches they cannot be inadvertently or accidentally withdrawn.

From the foregoing it will be seen that an effective device for the purposes set forth has been disclosed, by means of which sunken ships may be salvaged in a relatively rapid and safe manner.

Having thus described my invention and including its construction and application, what I claim as new and desire to secure by Letters Patent, is:—

1. In a device for the purpose described, in combination with a drill bar, of means for rotating and advancing said bars, said means permitting disconnection, a triangular support frame for said bar adapted to maintain the same substantially horizontal, a haulage cable passing through the upper member of said frame adjacent its base attached to said bar, and a gravity operated latch pivoted in said bar adjacent the drill end thereof.

2. In a device for the purpose described, in combination with a drill bar, of detachable means for driving and feeding said drill bar, a triangular frame having its base in immediate contact with the part to be drilled and containing openings through which said bar passes horizontally, a pivoted gravity latch in said bar adjacent the drill end thereof, and a cable engaging a recess in said bar and passing through the upper element of said frame.

3. In a device for the purpose described, an oblong rectangular diving bell having

upper and lower compartments, support bars extending diagonally from the outer corners of said bell, rack and pinion adjustment for said bars, means for maintaining said bars when adjusted, a plurality of 5 motors in the lower compartment, shafts driven by said motors, said shafts projecting through said bell, means for advancing

or retracting said shafts, drill bars detachably engaging said shafts, and means for 10 guiding said bars, said means also acting to maintain said bars horizontal after the retraction of said shafts.

In testimony whereof I have signed my name to this application.

CHARLES E. DRAKE.
